UNITED STATES PATENT OFFICE.

M. ELMER STEPHENSON, OF BOSTON, MASSACHUSETTS.

FLOWER-STAND.

SPECIFICATION forming part of Letters Patent No. 319,339, dated June 2, 1885.

Application filed December 24, 1884. (No model.)

To all whom it may concern:

Be it known that I, M. ELMER STEPHENSON, a citizen of the United States, and a resident of Boston, in the county of Suffolk and State of Massachusetts, have invented certain new and useful Improvements in Flower-Stands; and I do hereby declare that the following is a full, clear, and exact description of the invention, which will enable others skilled in the art to 5 which it appertains to make and use the same, reference being had to the accompanying drawings, which form a part of this specification, and in which—

Figure 1 is a perspective view of my improved flower-stand, with dotted lines indicating the reversed position of the same. Fig. 2 is a longitudinal transverse sectional view of the same. Fig. 3 is a vertical sectional view taken through one of the shelves or brackets 10 and the support for the same. Fig. 4 is a transverse sectional view taken on the line xx in Fig. 3; and Fig. 5 is a side view of the complete device, showing the shelves arranged in a horizontal position.

25 The same letters refer to the same parts in all the figures.

This invention relates to flower brackets or stands; and it has for its object to produce a device in which the supporting-shelves shall 30 be mounted upon a pair of swinging arms, which may be reversed, so as to reverse the relative upper and lower positions of the end and adjoining shelves.

The invention consists in the improved construction of the device, whereby it is made 35 separable, so as to enable it to be packed in a small space for transportation, or when not in use.

The invention further, and finally, consists 40 in the improved construction and arrangement of the details of the same, having for their object to produce a device which shall possess superior advantages in point of simplicity, durability, and general efficiency, as will be 45 hereinafter fully described, and particularly pointed out in the claims.

In the drawings hereto annexed, A A designate a pair of side pieces or brackets, having legs that rest upon the floor, and connected 50 detachably by a brace, B, near the bottom, secured transversely between the said side pieces by means of screws CC entering through

the ends of the same. The tops of said legs are horizontal, and connected by one of the shelves, as described below. The shelf thus 55 does double duty as brace and shelf.

To the inner side of each of the side pieces, A A, is pivoted a pair of arms, D D, parallel to each other, and provided with brackets E E, pivoted vertically to their outer sides, and 60 provided at their upper edges with longitudinal dovetailed flanges F F. The lower ends of the brackets E E, being pivoted to each of the pivoted arms D D, will retain a vertical position at any position to which the said 65 arms may be adjusted.

Boards or shelves are provided, the under sides of which, near their ends, have dovetailed grooves G G, adapted to fit over the flanges F F of the brackets E E. These grooves and 70 flanges serve to keep the boards in place, and also serve to brace the stand laterally, and thus enable the stand to be put together with the fewest possible pieces, and still preserve the requisite strength. The said boards or 75 shelves (which are designated by letters H H) are thus made adjustable and detachable from the device, so that a greater or larger number of shelves may be used, according to the numbers and sizes of flower-pots or other devices 80 which it is desired to exhibit.

A hook or hooks (designated by letters K) are to be employed for the purpose of retaining the swinging beams in any position to which they may be adjusted.

85 From the foregoing description, taken in connection with the drawings hereto annexed, the operation and advantages of this invention will be readily understood.

The construction is simple and inexpensive. 90 The device may be readily taken apart for adjustment or transportation, the shelves being detachable by simply sliding them off their supports, and the frame being likewise readily separable.

95 When the device is used as a flower-stand, which is its primary intention, the stand may be easily adjusted and reversed for purposes of exhibition, watering, arranging, and the like; but the device is equally useful and 100 efficient for a variety of other purposes—such as, for instance, an exhibition-stand for show-windows, which enables such windows to be dressed from the inside, reserving, of course,

the fact that articles to be exhibited should be arranged separately upon the separate shelves. The device will be found useful and efficient for many other purposes which will readily suggest themselves.

5 I am aware that display-stands have been constructed with parallel frames, having two of the pieces of each frame pivoted at their centers to an upright stand, and I do not claim 10 such construction; but

I claim and desire to secure by Letters Patent—

15 1. The combination, with two upright legs, the tops of which are horizontal and provided with dovetailed flanges, of a horizontal shelf having dovetailed grooves on its under side, near its ends, engaging with and connecting the tops of said legs, a brace connecting said legs near their bottoms, two pairs of parallel 20 arms pivoted at their centers to said legs, a number of bracket-shelves pivotally secured to said arms, and means for retaining said

arms in an inclined or a horizontal position, substantially as and for the purpose set forth.

2. The combination, with two upright legs 25 having horizontal dovetailed tops, and connected at their bottoms by a removable brace, of two pairs of parallel arms centrally pivoted to said legs, a number of vertical brackets pivoted to said arms, having their tops horizontal and dovetailed, a number of shelves having dovetailed grooves near their ends, fitting on the tops of said brackets and legs, and a hook secured to the said legs, to engage with pins in said parallel arms, substantially as and for 30 35 the purpose set forth.

In testimony that I claim the foregoing as my own I have hereunto affixed my signature in presence of two witnesses.

M. ELMER STEPHENSON.
